UNITED STATES PATENT OFFICE.

GEORGE L. THOMPSON, OF CHICAGO, ILLINOIS.

DESIGN FOR A BICYCLE-FRAME.

SPECIFICATION forming part of Design No. 29,243, dated August 16, 1898.

Application filed July 5, 1898. Serial No. 685,176. Term of patent 7 years.

To all whom it may concern:

Be it known that I, GEORGE L. THOMPSON, of Chicago, in the county of Cook and State of Illinois, have invented and produced a new and original Design for a Bicycle-Frame, of which the following is a specification.

My novel design consists in a bicycle-frame of the general type commonly known as the "diamond" frame, and embraces as its distinctive features the novel design produced by the conformation of the rearfork members a' , respectively, embodied in a frame made in other respects as usual—*i. e.*, made of ordinary circular tubing.

In the present design each fork member is made of angular contour in cross-section, so as to present to view a plurality of flat faces a^2 , extending throughout the principal part of its length and having end portions a^3 , which are made smooth and of generally circular form in cross-section, substantially as shown in the accompanying drawings, wherein—

Figure 1 is a perspective view of the frame as a whole, and Fig. 2 is a transverse sectional view taken on line 2 2 of Fig. 1. 25

The flat faces are arranged symmetrically and substantially coextensive with each other and merge into the smooth end portions a^3 in the form of gracefully-tapered points a^4 , thereby contrasting with the angular-shaped portions of the forks and accentuating the characteristic appearance of the design as a whole.

I claim as my invention—

The design for a bicycle-frame, substantially as herein shown and described. 35

In testimony that I claim the foregoing as my invention I affix my signature hereto, in the presence of two subscribing witnesses, this 30th day of June, A. D. 1898.

GEORGE L. THOMPSON.
